UNITED STATES PATENT OFFICE.

HOMER H. WITHROW, OF BROOKS, WEST VIRGINIA.

KEY TAG.

Application filed August 14, 1923. Serial No. 657,385.

To all whom it may concern:

Be it known that I, HOMER H. WITHROW, a citizen of the United States, residing at Brooks, in the county of Summers and 5 State of West Virginia, have invented certain new and useful Improvements in Key Tags, of which the following is a specification.

In carrying out the present invention it 10 is my purpose to provide a tag for attachment to keys wherein advertising means may be associated therewith for displaying to the public certain commodities or in most instances the salient features of the 15 hostility to which that particular key carrying the tag belongs.

The primary object of the invention is the provision of such a tag that is extremely simple of construction and one that 20 may be manufactured and marketed at relatively small cost, the present tag being additionally characterized by the fact that the advertising carrying plates may be removed and renewed whenever desirable.

25 The nature and advantages of the invention will be better understood when the following detailed description is read in connection with the accompanying drawing, the invention residing in the construction, combination and arrangement of parts 30 as claimed.

In the drawing forming part of this application, like numerals of reference indicate similar parts in the several views, and 35 wherein:

Figure 1 is a top plan view of my improved tag.

Figure 2 is a side elevation thereof, and

40 Figure 3 is a detail longitudinal cross-section thereof.

With particular reference to the drawing, my novel tag embodies a base plate 5, of fiber or other appropriate material that is preferably substantially diamond 45 shape and that is provided with a removable channel metallic rim 6. As shown more clearly in Figure 1, this rim 6 is formed around the edges of the base plate 5 and has its meeting edges formed with laterally 50 extending ears 7 that are provided with alined openings for the reception of a bolt and nut fastener 8.

The top surface of the base plate 5 is channelled at 9 for the reception of a sub-

stantially diamond shape advertisement 55 bearing sheet 10, it being noticed from a consideration of Figure 1 that said sheet 10 terminates at its front end slightly inwardly of the similar end of said base plate 5.

Upon the top side of the base plate 5, 60 and in position over the advertisement bearing sheet 10 is a substantially diamond shape strip of transparent material 11 that is maintained in position through the medium of a metallic rim 6.

The base plate 5 adjacent its front end is provided with an opening through which extends a hollow rivet 12 the said transparent sheet 11 being also formed with an opening whereby a key ring 13 may be 70 positioned therethrough, the said rivet 12 preventing wear upon said base plate.

In view of the foregoing when considered in conjunction with the accompanying drawing it will at once be apparent that the 75 advertisement bearing strip 10 may be removed for allowing a new advertisement bearing sheet to be associated with the back- 80 ing 5 by removing the bolt nut fastener 8 from the ears of said metallic rim 6 after which this rim may be bent away from the marginal edges of the back.

I have shown and described the most practical embodiment of the invention with which I am at present familiar, but it 85 is nevertheless to be understood that in the future practice of the invention minor changes may be made therein without departing from the spirit and scope of the appended claim.

Having described my invention, what I 90 claim and desire to secure by Letters Patent, is:

A key tag comprising a plate provided at its side surface with a countersunk channel all of the edges of which are spaced from the adjacent and corresponding edges of the plate, a transparent sheet disposed over the plate and the channel, a relatively rigid frame binding the edge portions only 95 of the sheet and plate together, and having its edges disposed beyond the edges of the channel, and an eyelet rivet passing transversely through the plate and sheet and disposed beyond the end of the channel. 100 105

In testimony whereof I affix my signature.

HOMER H. WITHROW.
